mesne assignments, to Grove Regulator Com-
pany, Oakland, Calif., a corporation of Cali-
fornia

Application August 15, 1949, Serial No. 110,349

4 Claims. (Cl. 277—55)

1

This invention relates generally to valves of the type adapted to control flow of fluid to and from a pressure receiving chamber or receiver.

In many instances it is desired to control the operation of an appliance by supplying or venting off fluid pressure from a fluid pressure operating chamber. For example fluid pressure operated valves are frequently provided with a pressure operating chamber to which air or other gas under pressure is supplied for retaining the valve in one of its operating positions, as for example in closed position. Suitable loading is provided whereby when the pressure is vented from the operating chamber, the valve moves automatically to its open position. Expansible tube valves of the type disclosed in Patents 2,353,143, 2,360,873 and 2,331,291 have an operating chamber to which fluid pressure can be supplied, or vented off, in order to secure operation of the valve between closed and open positions. Control valves for such appliances can be operated in various ways, as for example by a liquid float or other type of motive means. Assuming that the control valve includes a valve member which is movable in opposite directions between limiting positions, it is generally desirable that the valve move with snap or rapid action, particularly when moving in a direction to vent off pressure from the operating chamber of the appliance. Such snap action makes for more positive operation of the appliance, and prevents a throttling action on the part of the control valve, which in many instances is deemed undesirable.

It is an object of the present invention to provide a control valve of the above character which is capable of the desired snap action, but which secures this result without the use of the customary mechanical devices, such as toggle means or the like.

Another object of the invention is to provide a control valve of the above character which makes use of the pressure being vented off from the operating chamber, to secure the desired snap action.

Additional objects of the invention will appear from the following description in which the preferred embodiment has been set forth in detail in conjunction with the accompanying drawing.

Referring to the drawing:

Figure 1 is a side elevational view, in section, illustrating a control valve incorporating the present invention.

Figure 2 is a view like Figure 1, but with the

2

lower end removed, and showing the plunger in a different operating position.

The valve as illustrated in Figure 1 consists of a body 10, provided with the passages 11, 12 and 13. Passage 11 is adapted to be connected to the operating chamber of an appliance as described above, such as the jacket chamber of an expansible tube valve of the type disclosed in said patents. Passage 12 can be termed a vent passage, and may discharge to the atmosphere. Passage 13 is adapted for connection with the source of fluid pressure employed to supply pressure to the passage 11.

The movable valve member is in the form of a plunger 14 which is used in conjunction with a plurality of resilient O rings, substantially in the manner disclosed in my copending application Serial No. 100,225, filed June 20, 1949. In general the plunger consists of the two cylindrical portions 16 and 17, which are connected by the portion 18 of reduced diameter. Another cylindrical portion 19, is of reduced diameter, and extends beyond the plunger portion 17.

The body 10 is bored on several diameters to accommodate the plunger and the parts associated with the same. Thus the body is bored to provide the entrant bore 21, the bore 22 between the passages 11 and 13, and the bore 23 between the passages 11 and 12. In addition to these bores there is an enlargement 24 communicating with passage 13, and an enlargement 26 communicating with passage 11. Beyond the bore 21 there is a bore 27 serving to house certain parts as will be presently described, and this end of the body carries a removable closure 28.

A resilient O ring 31 surrounds the plunger portion 19, and is compressed radially to form a seal between this plunger portion and the adjacent surface of the bore 23. This O ring is loosely accommodated in an annular recess 32 formed between the end faces of the metal retaining ring 33, and the sleeve 34. The retaining ring 33 is held in place on the plunger by the snap-on ring 36. Retaining ring 33 and sleeve 34 slidably fit within the bore 23, and take the thrust of the resilient O ring 31, when pressure is applied to the same.

Another resilient O ring 37 is disposed within the bore 22, and for the position of the plunger illustrated in Figure 2, it is compressed radially between the plunger portion 17 and the bore 22, to form an effective seal. This O ring is accommodated in an annular recess 38, which is formed between the metal retaining ring 39 and one end face of the metal sleeve 41. The sleeve 41 is pro-

vided with ports 42, whereby when the plunger is in the position shown in Figure 1, fluid may flow from passage 13 to passage 11.

Another resilient O ring 43 serves to form a seal between the bore 21 and the plunger portion 16. This O ring is accommodated in an annular recess formed between the other end of the sleeve 41, and the ported sleeve 44. Sleeve 44 is ported to facilitate introduction of lubricant. Sleeve 44 is recessed to accommodate the lubricant wiping ring 46, which in turn is held in place by the cover washer or ring 47. Washer or ring 47 is held in place by the cover member 28.

The projecting end portion 49 of the plunger is arranged for connection with some suitable motive means, such as a pivoted lever which carries a liquid float. A sleeve 51 is shown attached to the plunger portion 49, and a collar 53 adjacent one end of this sleeve forms a limiting shoulder, which for one limiting position engages the stop shoulder 54. Sleeve 51 carries another shoulder 55 which for the other limiting position engages the adjacent face of closure 28. Figures 1 and 2 illustrate the two limiting positions.

The valve described above is similar to one of the embodiments illustrated in my aforesaid copending application. For the position of the plunger illustrated in Figure 1, passages 13 and 11 are in communication, while passage 11 is sealed with respect to the vent passage 12. For the position shown in Figure 2, passage 13 is sealed with respect to passage 11, while passage 11 is in free communication with passage 12.

In addition to the parts described above, a pressure relief valve 56 is provided which serves to control discharge of fluid from the passage 12. This relief valve may vary in construction, but it should be such as to seal the passage 12 until a pressure substantially greater than atmospheric is applied to the same, after which the relief valve opens and vents the passage 12. In the construction illustrated the relief valve consists of a fitting 57 which is threaded into the passage 12. The fitting carries a cylindrical stud 58, on which a resilient rubber tube 59 is fitted. The rubber tube is normally tensioned into sealing engagement with the periphery of the stud 58. The stud 58 is provided with the connecting ducts 61 and 62, the latter communicating through the periphery of the stud. The periphery of the stud is also provided with a small bleed groove 63, and with an enlarged head or flange 64, which serves to prevent dislodgement of the rubber tube 59.

In order to describe the manner in which my valve operates, it will be presumed that the passage 11 has a direct closed connection with the operating jacket of a valve of the type disclosed in the aforesaid patents. Passage 13 can connect to a source of air or gas pressure ample to insure operation of the expandible tube valve. The projecting end of the plunger 14 is connected to suitable operating means which is to be used for controlling operation of the expandible tube valve, such as a lever connected to a liquid float.

For the position of the plunger illustrated in Figure 1, pressure in passage 13 is transmitted to passage 11 and from thence to the jacket chamber of the expandible tube valve. Therefore the expandible tube valve is maintained in closed position. When the plunger is moved to the other limiting position shown in Figure 2, the plunger portion 17 enters into sealing engagement with the resilient O ring 37 to interrupt communication between the passages 13 and 11, and O ring

31 breaks its sealing engagement with the bore 23. This causes fluid under pressure from passage 11 to discharge into the passage 12, and because of the pressure required to open the relief valve 56, pressure initially builds up to thereby apply force to the lower end of the plunger. This serves to unbalance the plunger, thus urging the same upwardly to the limiting position shown in Figure 2. Upward movement of the plunger occurs relatively rapidly, or with snap action. Immediately after or in conjunction with upward movement of the plunger to its limiting position, the pressure in passage 12 reaches such a value as to open the relief valve. The relief valve opens by virtue of radial distortion of the resilient tube 59, in the region of the duct 62, thus permitting the gas to discharge relatively freely to the atmosphere. The venting capacity of the relief valve is ample to vent off pressure from passage 11, and the operating jacket chamber of the expandible tube valve, whereby after a short interval the jacket pressure has been vented down to a pressure sufficiently low to permit the expandible tube to expand and flow to occur through the same. When the pressure in the passage 11 drops down below the value required to hold the relief valve open, the relief valve automatically closes, and thereafter further restricted venting occurs through the bleed groove 63. Thus the pressure in the passages 11 and 12 falls to atmospheric. Now assuming that the plunger is subsequently moved back to the position shown in Figure 1, such movement occurs under substantially balanced conditions, because of the absence of pressure in the passage 12.

In general it will be evident that my control valve is well adapted for the remote operation of various fluid pressure operated appliances, such as expandible tube valves of the type previously mentioned. To state a particular example, the expandible tube valve may be connected to discharge liquid from the lower portion of a high pressure gas-liquid separator, such as is commonly used in the oil fields. The plunger of the control valve can be connected to a float which is responsive to the level of oil in the separator chamber. When the liquid level reaches a predetermined level, the plunger is moved upwardly to connect the passages 11 and 12, and to vent through the relief valve 56, with snap upward movement of the plunger in the manner previously described.

The subject matter disclosed and not claimed herein is disclosed and claimed in my copending application Serial Number 3,728, filed January 22, 1948, and entitled "Valve Construction."

I claim:

1. In a valve of the plunger type adapted to vent pressure from a pressure chamber, a valve body having a first passage for connection to the chamber and also having a second vent passage, the body having a bore connecting said passages, a valve plunger movable axially between limiting positions relative to the body, the plunger in one position extending into the bore to seal against communication between said passages and in its other limiting position permitting such communication, the inner end of the plunger presenting a substantial fluid pressure area to pressure in the vent passage, the outer end of the plunger being exposed to atmospheric pressure, and a normally substantially closed pressure release valve communicating with said passage and serving to control venting of fluid therefrom, whereby pressure is applied to said pressure area when the plunger

is moved to permit flow of fluid from the first passage to said vent passage.

2. In a valve of the plunger type adapted to vent pressure from a pressure chamber, a valve body having a first passage for connection to the chamber and a second vent passage, the body having a third passage adapted for connection with a source of fluid pressure, a bore extending into the body, said bore having one portion thereof communicating between said first passage and said vent passage and another portion communicating between said first passage and said third passage, a valve plunger extending into the body and movable between limiting positions, the plunger in one of its limiting positions extending into said first named portion of the bore to seal communication between the first and second passages and in its other limiting position permitting such communication and extending into the second bore portion to seal communication between said first and third passages, one end of the plunger presenting a substantial fluid pressure area to pressure in the vent passage, the other end of the plunger extending from the body and being exposed to the atmosphere, and a normally substantially closed pressure relief valve communicating with said vent passage and serving to control discharge of fluid from the same, said relief valve requiring application of substantial pressure above atmospheric to open the same, said relief valve serving to apply a back pressure on said pressure area when the plunger is moved to permit flow of fluid from the first passage to the vent passage.

3. In a valve of the plunger type adapted to vent pressure from a pressure chamber, a valve body having a first passage adapted for connection to the chamber and also having a second vent

passage, the body having a bore connecting said passages, a valve plunger movable axially between limiting positions relative to the body, the plunger in one position extending into the bore to seal against communication between the passages and in its other limiting position permitting such communication, one end of the plunger presenting a substantial fluid pressure area to pressure in the vent passage, a normally substantially closed pressure relief valve communicating with said passage and serving to apply back pressure on said pressure area when the plunger is moved to permit flow of fluid from the first to the second passage, and a bleed duct communicating between said vent passage and the atmosphere.

4. A valve as in claim 2 in which a bleed duct connects between the vent passage and the atmosphere.
